UNITED STATES PATENT OFFICE

2,288,520

CASH REGISTER

Helmut Geller, Berlin-Charlottenburg, and Hans Driescher, Berlin-Spandau, Germany, assignors to The National Cash Register Company, Dayton, Ohio, a corporation of Maryland

Application August 11, 1939, Serial No. 289,662
In Germany August 17, 1938

27 Claims. (Cl. 235—3)

This invention relates to improvements in cash registers and accounting machines of the general type illustrated in United States Letters Patent to Ernst Breitling Nos. 1,760,870, 2,052,444 and 2,064,147 granted respectively on June 3, 1930; August 25, 1936, and December 15, 1936.

It is generally the custom for public utility companies that supply communities with electric current, gas or water to furnish their numerous subscribers with a periodical statement of their accounts.

The consumption is first calculated from the previous and present readings of the meter and the amount of the bill to be presented to the consumer must then be obtained from this consumption by multiplying the units of consumption by the charge per unit. Such product must be obtained independently of the accounting machine, and is usually done by reading from multiplication product tables.

To avoid the resulting loss of time by such methods and the possibility of incorrect reading, it is an object of the present invention to provide means whereby the product is automatically selected and shown enlarged from reduced product tables provided in the machine according to factors calculated in the machine and/or set up as desired.

It is therefore an object of this invention to provide in a machine having a balancing mechanism, means controlled thereby when the same is set to zero, for automatically indicating the balance or amount taken therefrom and for automatically selecting the product from a chart or table of products, the selected product being based on or controlled by said balance.

Another object of this invention is to provide a plurality of product tables based on various rates with means for selecting the table to be used and means for selecting an individual product from the selected table, the selection of said individual product being controlled by differential mechanisms controlled by the consumption of the commodity being used.

Fig. 1 is a perspective view of a portion of an entry machine with the cabinet or casing removed.

Fig. 2 is a plan view of the consumption indicating apparatus.

Fig. 3 shows the electrical connections for the indicating apparatus for indicating the consumption calculated by the machine.

Fig. 4 is a front view of the consumption indicating apparatus.

Fig. 5 is a side elevation of the ratchet wheel

connected with the reduced product table discs of Fig. 8, and the corresponding catch or stop device in the inoperative position.

Fig. 6 is a side elevation of the consumption indicating apparatus.

Fig. 7 shows a part of the ratchet wheel of Fig. 5 and the catch or stop device in the operative position.

Fig. 8 shows a product table for consumption values of 0-499 at a price of 0.075 cent per unit of consumption.

Fig. 9 is an elevation of the discs carrying the reduced product tables.

Fig. 10 is an elevation of two collector or commutator rings with the contacts sliding thereon and mounted thereon with the discs of Fig. 9.

Figs. 11A and 11B together constitute a plan view of the complete arrangement for indicating a value from a product table.

Fig. 12 is a wiring diagram for indicating a value from a product table.

Fig. 13 is a section on line 13—13 of Fig. 15.

Figs. 17 is a section on line 17—17 of Fig. 14.

Fig. 18 is an elevation of the shutter or screen and its setting mechanism for selecting a line.

Fig. 19 is a section through a modified form of a table selecting mechanism driven from the hundreded position.

Fig. 20 is a cross section through said modified form of table selecting mechanism driven from the unit position.

Fig. 21 is a cross section through said modified form of the shutter adjusting mechanism driven from the decimal position.

Fig. 22 is a front elevation of said modified form of the table selecting mechanism driven from the hundreded position.

Fig. 23 is a front elevation of said modified form of the table selecting mechanism driven from the unit position.

Fig. 24 is a plan view of said modified form of the table selecting mechanism.

Fig. 25 is an enlarged reproduction of the tables of said modified form, for the units 00, 10, 20, 30, 40, 50, 60, 70, 80, and 90, based upon the rate of .075 per unit.

Fig. 26 is a diagrammatic showing of the product indicating mechanism according to a second modification.

Fig. 27 is a diagram showing the connection for the projection apparatus of said second modification.

The entry machine comprises a number of rows of amount keys 61 (Fig. 1) and several rows of special keys 62 for adding mechanism selection. By means of the amount keys the old and new state of the meter readings with the opposite indications are carried into the balance mechanism 63 in two consecutive operations of the machine. The consumption calculated in the balancing mechanism 63 is printed in the following machine operation by setting the balancing mechanism to zero. In order that all the amounts necessary to the preparation of a customer's bill may be obtained simultaneously during this operation, the product table upon which certain of these amounts are based is selected, before the operation is begun, under control of special keys 64 according to the tariff or charge per unit. These special keys 64 comprise a complete units row of nine digit keys and a tens row containing four keys. It is thus possible to select forty nine different product tables by means of the special keys 64.

Consumption indicating apparatus

By setting the balance mechanism (Fig. 1) to zero, differential members 65, connected with the racks 66 which in turn are connected with the type wheels of the printing mechanism are set in a known manner (see last two Breitling patents cited above). In the construction shown, an arrangement is also provided to make the printed consumption visible also by means of a special indicating device. Inasmuch as it is assumed that the monthly consumption does not as a rule exceed a three position value, only the three lowest racks 66 are connected with the indicating mechanism. At the end of each rack 66 of the three lowest values there are contact springs 67 and 68, each contact spring 67 being adapted to slide over a series of fixed contacts 69 and each spring 68 adapted to slide over a series of fixed contacts 70. The three rows of fixed contacts 69 (Fig. 3) are each connected by leads 71 formed into a cable with a set of incandescent lamps 72, so that after finally setting the three lowest value racks 66, lamps 72 can be illuminated corresponding to this setting. Current is passed from the positive line connection 86 of the source of supply, through the contact spring 92 and fixed contact 91 (spring 92 being moved into contact with the fixed contact 91 by the rack 90 when taking an amount from the balancing mechanism, as later stated), over a conductor 81, through the contact springs 67 which are connected by means of insulating members 73 with racks 66 through the leads 71, lamps 72 to the point 83 of the negative side.

It would be possible to carry a plate with the corresponding figure and adapted to be illuminated translucently, in front of each lamp 72. This, however, would have the disadvantage that the figures of a three-figure number indicated in this manner would not appear in a row. Therefore, in order to make possible the indication of three-figure numbers in a horizontal row by means of the three rows of incandescent lamps 72, each row of lamps 72 is positioned in a curved support 74 (Fig. 6). The curvature of support 74 corresponds to an arc which is constructed about the centre of the indicating point 76 of a ground glass disc viewing screen 75. But, also viewed in a horizontal plane, the three

lamp supports are disposed along an arc (Fig. 2) which is constructed about the central line of a diapositive 77. The sole purpose of this arcuate arrangement of the three lamp supports 74 is to indicate three different figures of a three-figure number by means of the diapositive 77 (Fig. 4) having only a single vertical number row. As clearly shown on Fig. 2 the rays passing from the lamps of the three rows meet in the diapositive 77, to again separate and be distributed over the complete width of the indicating point 76 of the ground glass disc or viewing screen 75. The diapositive 77 is located at the narrowest point of a funnel 78 which is attached by means of screws 79 to the incandescent lamp supports 74.

Inasmuch as the three lowest value racks 66 are also set in entering the old and new state of the meter at numerical value, this value would also be indicated similarly on the disc 75 if current were passed continuously to the contact springs 67 (Figs. 1 and 3). However, the indication of the three lowest orders or values of the old and new state of the meter is of no importance; and therefore the arrangement is such that only when the consumption is printed, that is, during the operation through which the balancing mechanism is set to zero, are contact springs 67 connected with the current source. For this, use is made of a rack 90 which is set by the differential member 65 of a predetermined special differential mechanism, the function of which is to select an accumulative adding mechanism for the reception of the amount from the balancing mechanism. Inasmuch as the adding mechanisms for the reception of such amounts assume the two outermost positions in their series, the rack 90 set by this special differential mechanism comes into a predetermined setting range only when taking an amount from the balancing mechanism. Provided in this range is a fixed contact 91 with which a contact spring 92 connected by means of insulating members 89 (Figs. 1 and 3) with rack 90 can come in contact. The circuit to the contact springs 67 is closed only when such movement takes place. This circuit, as above explained, as from point 86 (Fig. 3) on one side of the source of supply, through the spring 92, fixed contact 91 (at this time contacted by 92), over conductor 87, through the spring 67, selected contacts 69, associated leads 71, and lamps 72, to the point 83 of the other side of the source of supply. As a result, indication by means of the lamps 72 can take place only during the machine operation serving to set the balancing mechanism to zero.

Selection of the product tables

As stated, the product table which contains all the products formed with the corresponding price per consumption unit is selected under control of the special keys 64 as the sum to be billed to the consumer. Fig. 8 shows such table for unit price of .075 cent, in which all products are put in round numbers at whole cents. Inasmuch as a three-figure number is provided for, the consumption the table must actually show a thousand different values, that is, the products of all numbers in the range of 0 to 999 with the factor 0.075. In the exemplary embodiment shown, however, it is assumed that, as a rule, a monthly consumption of 499 units is rarely exceeded, so that the product tables need contain only 500 values.

The diapositives 93 (Fig. 9) containing these

tables suitably reduced are attached to the periphery of a rotatable disc 94 secured to a shaft 96, and can be carried into the range of a projection apparatus 95. In order to select a predetermined product table; that is, to hold a predetermined diapositive 93 in the range of the projector 95, a ratchet wheel 97 (Figs. 5, 7 and 11B) is also attached on the shaft 96 carrying the disc 94. A stop 99 can be carried into the range of the ratchet teeth 98 of wheel 97. For this purpose the stop 99 is attached rotatably at the end of a piston rod 100, which slides in a brake cylinder 101. Associated with the stop 99 is a magnet 102 which upon being energized rocks the stop 99 counter-clockwise about its pivot pin, until pins 103 (see also Fig. 11B) extending from both sides thereof contact the lower horizontal edges of two fixed plates 104. In this manner the upwardly extending extension of the stop 99 passes into the range of the ratchet teeth 98 (Fig. 7).

In order to hold the desired diapositive 93 in the range of the projector 95 the magnet 102 must be energized according to the depressed special key or keys 64. A rack 105 (Fig. 1) is set from the unit key row 64, and a contact spring 107 attached to said rack 105 by means of an insulating member 120 is adapted to slide over a series of fixed contacts 108. A contact spring 109, which co-operates with a series of fixed contacts 110, is also attached by means of an insulating member 121 to a rack 106 set by the tens row 64. The five fixed contacts 110 are connected by the leads 111 (Fig. 12) forming a cable 112, with the five annular members of a collector ring 113. Likewise, each fixed contact 108 is connected by one of the leads 114, combined to a cable 115, with each group of five of the fifty plates of a second collector ring 116, whereby each two of the plates connected with the same contact 108 are removed ten plates from each other. Ten plates of the outer collector ring 116 correspond to each annular member of the inner ring 113. The two collector rings 113 and 116 are mounted on a fixed plate 117 (Figs. 10 and 11B) concentric with the shaft 96, on which latter, in addition to the disc 94 carrying the diapositives 93, and the ratchet wheel 97, there is also attached an arm 118 which carries two conductively interconnected brushes 119 which, however, are insulated from arm 118. On rotation of arm 118 the one brush slides on the plates forming the inner ring 113 and the other on the plates forming the outer ring 116. When the brushes simultaneously engage plates which are connected through the fixed contacts 108 and 110 with the contact springs 107 and 109, a circuit is closed which is utilized to energize the magnet 102 and thereby hold ratchet wheel 97 and disc 94.

It is, of course, obvious that the disc 94 is to be thus held only during the machine operation for taking the sum from the balancing mechanism. Therefore, there is a second contact spring 130 (Figs. 1 and 12) on rack 90 which comes in contact with a fixed contact 131 on extracting sums from the balancing mechanism. Since the plus (+) pole of the current source is connected with the contact spring 130, on its contact with the fixed contact 131 the circuit is passed further over a conductor 132, a condenser 133 and the winding 135 of a relay 134 to the minus (-) pole of the current source. If the winding 135 is set under current by the establishment of this circuit the switch 136 of relay

134 is closed. The following circuit is thereby formed: From the plus pole of the current source through a choke 137, a condenser 138, to the negative side of the line. The circuit also is from the choke 137, through the switch 136 of the relay 134, a conductor 139, the winding of the magnet 102, a conductor 140, the contact spring 109, one of the fixed contacts 110, the corresponding conductor 111 and the corresponding plate of the collector ring 113, the two brushes 119 of arm 118, the plates of the outer ring lying in the range of the annular members of ring 113 connected with contact spring 109, which plates of said outer ring 116 are connected over a conductor 114 and a fixed contact 108 with the contact spring 107, then further over a conductor 141, a switch 142 and two conductors 143 and 144 to the minus pole of the current source. The switch 142 is open as long as a switch 145 for the motor circuit of the machine is closed. Switch 142 is closed only when switch 145 is opened, which indicates the completion of the entry operation of the machine. The circuit for the winding of magnet 102 can thus not become active before this. Switch 142 is provided to permit the activity of the circuit for the winding of magnet 102 only when the final adjustment or differential setting of the racks 105 and 106 is attained.

If the described circuit is established and current passes through the winding of magnet 102, stop 99 is raised and its upwardly directed extension carried into the range of the teeth 98 of ratchet wheel 97. In order to produce shock-free stopping of wheel 97 the tooth 98 first contacting with the upward extension of stop 99 (Fig. 5) moves the latter together with the piston 100 to the left, whereby the cylinder effects a smooth braking, until a second upward extension 145 (Fig. 7) is applied against bent down flaps of a fixed block 147. When this passes into the position shown on Fig. 7 the corresponding diapositive 93 is exactly in the ray or beam path of the projector 95. During the interval from the raising of the stop 99 until it is moved into the left end position determined by the block 147 the outer brush 119 has again left the conductive plate of ring 116 through which the circuit to the magnet 102 had been made, thereby de-energizing said magnet 102. This, however, does not change the active position of stop 99, as the latter is held in raised position by friction with the active ratchet tooth 98.

The rotation of the shaft 96 with the disc 94 and wheel 97 attached thereto is effected by a continuously rotating motor 148 (Figs. 11B and 12) which can be arrested by means of the ratchet wheel 97. In order to prevent shocks from reaching the motor 148 a spiral spring 149 (Fig. 11B) is interposed between a shaft 160, driven by motor 148 and the shaft 96. If the contact spring 130 (Fig. 12) is removed from the fixed contact 131, during the machine operation following the printing of the consumption, it comes in contact with a fixed contact 161, so that a circuit is closed from the plus side, over a conductor 162, a condenser 163 and the winding 164 of a relay 165 and conductor 166 to the negative side. The winding 164, through which current passes, shifts the two switches 167 of the relay 165 and thereby reverses the rotational direction of the motor 148, so that the shaft 96 with the ratchet wheel 97 (Figs. 5 and 7) describes a counter-clockwise movement. The active ratchet tooth 98 is thereby removed from

the upward extension of stop 99, whereby the latter resumes its normal position through the action of its spring 168. The interposed condenser 163 prevents current from flowing continuously through the winding of the relay 165. When the condenser 163 is charged a state of equilibrium is established, and current ceases to flow through the winding 164, whereby both switches 167 resume their normal positions; and the motor 148 is again shifted to normal rotation. The shaft 96 then rotates until the stop 99 is again carried into the range of the teeth 98 of ratchet wheel 97.

Selection of a predetermined product from the selected table

Assuming that a consumption of 367 units has been computed by the balancing mechanism, a value of \$27.53 will be given by the eighth column from the left and the thirty-seventh line from the top of the table according to Fig. 8. It must thereby be kept in mind that said table is so greatly reduced in dimensions that its height is about .59 inch and its width .39 inch on a diapositive 93.

In order to obtain the indicated value of \$27.53, it is first necessary to get the eighth column from the left from the table of Fig. 8. For this purpose use is made of a mirror 169 (Figs. 11A, and 14 to 17) which is connected with an armature 170 secured to a shaft 171. The mirror 169 is carried by a plate 159 having a short trunnion 151 and a long trunnion 152 to mount the plate 159 and mirror 169 in a bracket 153. Secured to the long trunnion is a worm wheel 154 driven by a worm pinion 155 secured to a shaft 156 mounted in a frame 157. Also secured to the shaft 156 is a knurled collar 158 driven by a knurled segment arm 159 fastened to the shaft 171. Thus, the mirror 169 is driven by the armature 170 when the magnet 172 is energized as will be later described. The armature 170 rotates between arms of a magnet 172, which is energized by means of a winding 173. The magnet 172 tends to impart a counter-clockwise movement to the armature 170 which is inclined with respect to the magnet arms. The magnitude of the rotation to be imparted to armature 170 and therewith mirror 169 is determined by a segment 174 attached to the shaft 171, said segment 174 having nine bent fingers 175. Fingers 176 of stop springs 177 are normally outside of the path of the fingers 175 of the segment 174. Co-ordinated with each spring 177 is a magnet 178 which when energized attracts the corresponding spring 177 and carries its finger 176 into the path of the corresponding finger 175. If current passes through the winding 173 and no magnet 178 is energized, the mirror 169, armature 170 and segment 174 can describe their complete counter-clockwise movement, which is determined by the tenth finger 179 contacting fixed stop 180. The finger 179 is normally applied against a stop 181, and thereby determines the inoperative position of the mirror 169, armature 170 and segment 174.

As shown by the circuit diagram of Fig. 12, the winding 173 lies in a circuit passing from the positive current source over a conductor 190, the winding 173, a second conductor 191 and a switch 192, to the conductor 144 which leads to the negative pole. The switch 192, like the switch 142, is closed only when the motor switch for the entry machine proper is opened.

The windings of the magnets 178 are all con-

nected with a conductor 193, which is connected with the positive pole of the current source. The other winding ends of the magnets 178 are connected, by conductors 194 combined into a cable 195, with the contacts 70 co-ordinated with the lowest value racks 66. Thus, a circuit can be closed from the positive pole of the current source over the conductor 193, that winding of a magnet 178 which is connected by one of the conductors 194 and the corresponding fixed contact 70 with the contact spring 68, conductor 141, switch 142 and the conductors 143 and 144 to the negative pole of the current source. The energization of a magnet 178 produced by such circuit causes the attraction of the corresponding stop spring 177, which therewith determines the movement of the mirror 169. The latter, on rotation, comes into a position such as to reflect from the diapositive 93 only a certain predetermined column of the product table (Fig. 8) sharply on a second mirror 196 (Figs. 12 and 15) which can rotate in a plane perpendicular to the rotational plane of the mirror 169. The mirror 196, like the mirror 169, is connected with an armature 197 which is rotatably mounted between the arms of a magnet 198. The winding 199 of this magnet is connected in parallel with the winding 173 by conductor 200 and 201. A segment 202 (Figs. 13 and 15), provided with four bent fingers 203, is connected with the armature 197, the segment 202 and armature 197 being secured to a shaft 204. There is provided a number of stop members 205 formed as armatures of electro magnets 206 and each 35 normally outside of the path of the fingers 203. On energization of a magnet 206 by means of its winding 207, through which current passes, the corresponding member 205 is carried into the path of the corresponding finger 203. One end 40 of each of the windings 207 is connected by a conductor 208 (Fig. 12) to the positive pole of the current source, while the other ends of windings 207 are connected by conductors 209 combined to a cable 210 with the four lowest value contacts 70 co-ordinated with the third rack 66 from the right. A circuit is thus established from the plus pole of the current source over the conductor 208, that winding 207 whose corresponding conductor 209 is connected through 45 the corresponding fixed contact 70 with the contact spring 68 of the third rack 66, also over the conductor 141, the switch 142 and conductors 143 and 144 to the negative pole of the current source. The function of the mirror 196 is to reflect, by the aid of a fixed mirror 189 (Fig. 11A), a group of ten consecutive lines from the column reflected by the mirror 169 from the product table, against a screen or shutter 211, having therein a plot or window 218, herein-after described in more detail, which allows a portion of the reflected group of lines to pass through the screen in the direction of the ground glass disc 75 (Figs. 11A and 11B). Since the product table of Fig. 8 has fifty lines in all, the line group mirror 196 must be capable of assuming five different positions. Four positions are determined by the four magnets 206, while the fifth is determined by a fixed stop 212 (Fig. 15) which limits the maximum travel of the segment 202. The latter can describe its maximum travel when the contact spring 68 of the third rack 66 passes to the fixed contact 70 corresponding to the figure 5 in this value position. This contact 70 is not connected with a winding 207 and therefore can not carry a con-

tact member 205 into the path of a finger 203. The five fixed contacts corresponding to the values 5-9 of the third contact row 70 are connected with a conductor 213 (Fig. 12) passing to a signal lamp 214, said conductor 213 being connected through a conductor 215 with the positive pole of a current source 216. The negative pole of this current source is connected by a conductor 217 with the contact spring 68 of the third rack 66. Thus, if the third rack 66 is set to a value exceeding the value 4 the signal lamp 214 lights, which shows that a value can not be taken for such consumption from a product table. This arrangement may be omitted if the product table according to Fig. 8 contains 1000 instead of 500 values.

The function of the screen or shutter 211 (Figs. 11A, 11B, 12 and 18) is to permit only a single one of the ten values reflected by the mirrors 196 and 189 to pass through its narrow slot or window 218 to the disc 75. The screen 211 is carried by a rod 230 attached on a shaft 231 of a small electric motor 232. The circuit for the motor 232 is from the plus line over conductor 233 then over conductor 234 and over a switch 235 and conductor 236 to the minus conductor 144. The switch 235 is so connected with the stop 99 for the ratchet wheel 97 that said switch 235 is closed when the stop 99 is raised. By means of the motor 232 the rod 230 and the shutter 211 are moved counter-clockwise out of the inoperative position shown in Fig. 18. A contact arc 237 provided with bent over lugs 238 (Fig. 18) is connected with the screen 211. Stops 239, with each of which an electromagnet 240 is co-ordinated, can be carried into the path of the lugs 238 (see also Fig. 11A). The windings 241 of the magnets 240 are connected, by conductors 242 combined to form a cable 243, with the fixed contacts 70 co-ordinated with the second rack 66 from the right (Fig. 1). The other ends of all the windings 241 are connected to a conductor 244 which is connected through a switch 245 of the relay 165, and a conductor 246 with the positive pole of the current source. When the switch 245 is closed a circuit passes from the positive pole of the current source over conductor 246, switch 245, conductor 244, that winding 241 in contact with the spring 68 of the second rack 66 through the corresponding conductor 242 and the corresponding fixed contact 70, further over the conductor 141, switch 142 and the conductors 143 and 144, to the negative pole of the current source.

Inasmuch as the circuits for the magnet windings 178 and 207 can be established on termination of each machine operation, after closing the switch 142, the mirrors 169 and 196 can be turned according to the adjustment of the corresponding racks 66. This positioning or adjustment of the mirrors 169 and 196 is, however, of no significance in connection with machine operations in which the consumption is not printed, as the ratchet wheel 97 is not stopped, but the disc 94 (Fig. 9) is in continuous rotation. This does not apply to the screen or shutter 211, as the motor 232 is under current only when the ratchet wheel 97 is stopped. The energization of a magnet 240 according to the adjustment of the corresponding rack 66 has no effect on the shutter 211 when the latter is in its inoperative position.

In connection with the machine operation following the indication of the consumption, how-

ever, the stop 99 must first be released by backward rotation of the wheel 97. Thus, the motor 232 can also run for this time, since the circuit for this motor 232 is held closed by the switch 235 until the stop 99 is released from the ratchet wheel 97. In order that thereby the screen 211 will not be held by a stop 239 energization of a magnet 240 is prevented in the following manner:

As stated, during the machine operation following the indication of the consumption, the contact spring 139 (Figs. 1 and 12) passes from the fixed contact 131 over to the fixed contact 161, so that current passes for a time over the conductor 162, over the condenser 163 and through the winding 164 of the relay 165. The energization of the relay 165 results not only in a periodical reversal of the rotational direction of the drive motor 148 for the shaft 160, but also in the opening of the switch 245, whereby the current to the windings 241 is cut off. The shutter 211 can thus be carried by the motor 232 into a position determined by a stop 247 (Figs. 11A, 12 and 17) before the switch 245 is again closed, after the current ceases to pass through the winding 164, and the magnet 240 corresponding to the position of the corresponding rack 66 can be supplied with current, and in which position of the screen 211 the ground glass disc 75 is completely darkened. In the initial or starting position, the rod 230 of screen 211 is applied against a fixed stop 248, being returned to such position when the magnets 241 are de-energized, whereby the disc 75 is also darkened.

Modified form

The selection of the involved product from the product tables provided on reduced scale in the machine can also be effected in purely mechanical manner, according to an exemplary construction described herewith with reference to Figs. 19 to 24.

The entry operation is the same, that is, the old and the new state of the meter together with the opposite notations are entered in the balancing mechanism in two consecutive machine operations and the thereby calculated consumption is printed in a third operation by setting the balance mechanism to zero.

In this case it is also assumed that the consumption between two meter readings does not exceed 499 units; and hence when the balancing mechanism is set to zero only the amount differential mechanisms of the three lowest positions (units, tens, hundreds) are actuated, whereby they set the three corresponding differential members, 260, 261 and 262 (Figs. 20, 21 and 19 respectively) to the value.

The units differential member 260 (Fig. 20) is connected through gears 264 and 265 with a gear 266 journalled on a shaft 267 (Fig. 23). The tens differential member 261 (Fig. 21) is connected through gears 268 and 269 with a gear 270 journalled on said shaft 267 and the hundreds differential member 262 (Fig. 19) is connected through intermediate gears 271 and 272 with a gear 273 journalled on the shaft 267.

The gear 273 of the hundred position (Figs. 19, 22 and 24) is connected through a train of gears 274, 275, 276, 277, 278 and 279 with a disc 280 journalled on a fixed shaft 281 in such manner that on a movement of the corresponding differential member 262 of one advance step, the disc 280 is given a fifth of a rotation counter-clockwise (Fig. 22). Five pins 282 are attached

at equal intervals on the disc 280 and on each pin there is loosely journalled a gear 283 and connected to the gears are table discs 284, 285, 286, 287 and 288. The five gears 283 are in constant mesh with a common gear 289 rotatable on the shaft 281. The transmission ratio between the gear 289 and the five smaller gears 283 is such that when, on rotation of disc 280, the gears 283 roll on the then standing gear 289, the gears 283 describe a complete revolution at each fifth of a revolution of disc 280. As a result of this combination each advance movement of the hundreds differential member 262 carries one of the discs 284 to 288 into the operative position above the shaft 281, whereby the discs 284 to 288, after the completion of each advance movement, or each fifth of a rotation of disc 280, are in their basic positions relative to disc 280.

The gear 289 is connected by a hub with a gear 290 (Figs. 20, 23 and 24) which is connected through an intermediate gear 291, a bevel gear drive 292, 293 and a hub 294 with a gear 295, which latter meshes with the gear 266 of the unit position. Through this drive connection, on each advance step of the unit differential member 260, the gear 289 is rotated clockwise in such manner as to impart a counter-clockwise movement of a tenth of a revolution to each of the five gears 283 with the table discs 284 to 288.

The disc 284 has ten product tables 301 to 310 (Fig. 22), the disc 285 has ten product tables 311 to 320, the disc 286 has ten product tables 321 to 330, the disc 287 has ten product tables 331 to 340 and the disc 288 has ten product tables 341 to 350. These tables are disposed at uniform intervals concentric to the corresponding pins 282, so that at each tenth of a revolution of the discs 284 to 288, that is, at each shift movement of the unit shift member 260, another one of the tables of the selected discs 284 to 288 comes into the operative position.

This operative position is vertically above the pin 282 of the selected one of the discs 284 to 288, and the table in this position is in a light ray thrown by an incandescent lamp 370 (Fig. 19) through optical lenses 371 and 372 toward a ground glass or the like plate 373. Then products are provided one below the other in a vertical column on each of the tables 301 to 350 (one of said tables being shown in Fig. 25), consisting of transparent material, which products can be projected through the optical arrangement toward the plate 373 so that a selected one of the products on the selected table can be read off by the operator from said plate.

In order to select the desired product from the ten products of each of the tables 301 to 350, selected and in an operative position, there is disposed between the selected tables 301 to 350 and the plate 373 an adjustable shutter or screen, 381 (Figs. 21 and 24) with a slot opening or window 382 which permits the passage only of a beam or ray for projecting a single product on the plate 373.

This shutter 381 is made in the form of a segment pivoted at 380. The shutter is provided with a gear segment 383 which is in continuous connection, through a gear drive 384, 385, 386 with the gear 270 which is geared to the differential member 261 of the tens position, and on each shift-movement of the member 261 is rocked so that only the desired line of the selected product table 301 to 350, and which has been determined by the setting of the member 261, is projected on the plate 373.

The same product tables as shown on Fig. 8, wherein the 500 products are divided into five groups of 100 each, which comprise the products of a certain basic price (for example 0.075 cent per unit) for consumption units of 000-099, 100-199, 200-299, 300-399 and 400-499, form the basis of this construction also. For each of these 5 groups of one hundred there is provided one of the five table discs 284 to 288, of which that disc is carried into the operative position by the shift mechanism of the hundreds position and the drive including the parts 262 and 271 to 279 connected therewith, which disc corresponds to the value taken from the hundreds position of the balancing mechanism in the third machine operation. If the hundreds position of the balancing mechanism has the value 0 the table disc 284 remains in the operative position, but if the value 1, 2, 3 or 4 is taken from the hundreds position of the balance mechanism the corresponding table disc 285, 286, 287, or 288 respectively is carried into operative position.

The products contained in a hundred group are divided into ten groups, wherein each group contains all the products of the consumption value with the same unit figure, as shown on Fig. 25 for the products of the values 00, 10, 20, 30, 40, 50, 60, 70, 80, 90, which corresponds to the first vertical column of the first hundred group of the product table shown on Fig. 8. Provided on each of the 50 product tables 301 to 350 of the table discs 284 to 288 corresponding to the five 100 (one hundred) groups is a vertical product slot, and the said discs are set according to the values contained in the units position of the balancing mechanism by the differential mechanism of the units position and the connected drive including the parts 260 to 266, 295, 294, 293, 292, 291, 290, 289 and 283, whereby the corresponding product table 301 to 350 of the discs 284 to 288 selected by the shift mechanism of the hundreds position passes into the range of the beam of the optical indicating mechanism.

The shutter 381 disposed behind the plate 373 is set by the differential mechanism of the tens position through the gear drive 261, 268 to 270, 386, 385, 384 and 383, according to the value taken from the tens position of the balancing mechanism, so that its slot or window 382 allows the plate 373 to show only that line of the selected table 301 to 350 which corresponds with this value. Through this arrangement the product determined by the consumption computed in the balancing mechanism is selected mechanically from the 499 products and projected on the plate 373 by the lighting of the lamp 370.

In order that the lamp 370 will light only during operations of the balancing mechanism said lamp is interposed in a circuit which, as in the first construction, is closed only when the entry machine is set for this operation.

If the products of more than 500 to 999 quantity units are to be indicated by this machine the arrangement described would then have to be arranged, preferably reflectively, whereby the tables 301 to 350 of these two indicating groups show the products of the consumption quantities of 500-999 units. In balancing mechanism operations, in order that only one of the two necessary plates 373 be illuminated, a contact path subdivided between the positions 400 and 500 and cooperating with the hundreds differential member 262, must be provided on the differential mechanism of the hundreds po-

sition, whereby the products of the values 0-499 units are indicated on the left plate and those of 500-999 units on the right plate.

For different basic prices a corresponding number of discs 280 with table discs 284 to 288 and the products corresponding to the base price on the tables 301 to 350, can be kept in reserve and, when necessary, substituted for the disc 289 of the base price mentioned (0.075 cent).

Second modified form

An arrangement for selecting and indicating the product corresponding to a certain base price and a certain quantity from a large number of products in the machine, can also be constructed, with the use of a table indicating apparatus of the type disclosed in United States patents to Fuller No. 1,163,748 granted December 14, 1915, and also in German Patent No. 524,340 granted to Fried Krupp on May 6, 1931.

Figs. 26 and 27 show such arrangement diagrammatically, which is briefly explained as follows:

When the amount (that is, the consumption—three position) calculated by carrying the old and new state of the meter into the balancing mechanism is printed in the third machine operation the table indicating apparatus should show the product formed from this consumed quantity and the base price involved.

The products of 000-999 consumption units and a certain base price are provided on ten tables 391 (Fig. 26) which together form a tariff or price group corresponding to this base price. According to requirements up to ten such tariff groups can be provided in the machine, one of which can be selected by pressing one of the special keys 64 (Fig. 1). Each of the ten tables 391 of a tariff group is provided with a hundred groups of products. The desired table 391 is selected by the differential mechanism of the hundred position according to the value contained in the hundred position of the balancing mechanism, by suitably moving the frame carrying these ten tables and raising the selected table 391 as described in the precedingly mentioned patents. The hundred products on this table are arranged in ten vertical and ten horizontal columns. In order to ascertain the desired product therefrom two shutters or slides 392 and 393 are provided, the horizontal slide 392 has a vertical slot 394 for each tariff group and the other, vertical slide 393 a horizontal slot 395 for each tariff group. The shutter 392 is connected with the differential mechanism of the unit position and is moved thereby so that its vertical slot 394 is set to the vertical column of the selected table 391 according to the value of the unit position.

In similar manner the vertically slideable shutter 393 is moved by the differential mechanism of the tens position so that its slot 395 is set to the line corresponding to the value of the tens position. As a result of this setting of the two shutters 392 and 393 the product determined by the unit and tens position of the balancing mechanism is selected on the table 391 selected by the hundreds position of the balancing mechanism, that is, released for illumination by the intersecting point of the two shutter slots 394 and 395.

In this arrangement each tariff group is provided with a projection apparatus of which, however, only that whose circuit is closed by the setting of the differential mechanism of the

special key rows 64, illuminates to throw the selected product on the ground glass plate 396 (Fig. 27). This circuit is from point 400, over conductor 401, spring contact 402, the selected fixed contact 403, its associated lamp 404, over conductor 405 to point 406.

This table indicating apparatus can also be constructed so that, for example, 500 products of a factor are provided on each table 391. With 10 five groups each of ten product tables, for example, there would thus be fifty tables each of 500 products. As in the first embodiment, the desired table must be selected by two special key rows 64. By pressing a key 64 of the first row 15 the associated table group is selected and by means of a key 64 of the second or tens row the corresponding table of this group is selected. The selected table is raised by the differential mechanism of the hundred position so that the line group corresponding to the hundreds value 20 therein is carried into operative position, that is, in front of the shutters 392 and 393. The product of these line groups of the table is selected as precedingly described, by the horizontally and 25 vertically slideable shutters 392 and 393, according to the state of the units and tens position of the balancing mechanism.

By arranging, for example, ten groups of tables, the number of product tables present in the machine can be increased 100 times, so that 50,000 in all are present for selection.

Instead of selecting by means of the tens and units position of the balancing mechanism it can also be done by means of the tens and units key rows. These two rows are common in all tables or table rows and effect the line and column selection through the movement of the two shutters 392 and 393.

While the form of mechanisms herein shown 40 and described are admirably adapted to fulfill the objects primarily stated, it is to be understood that it is not intended to confine the invention to the forms of embodiment shown and described, as it is susceptible of embodiment in 45 various forms, all coming within the scope of the claims which follow.

What is claimed is:

1. In a machine of the class described, the combination of a plurality of indicator plates 50 each having thereon data according to a system of determinants for locating them; a movable shutter adapted to be adjusted in accordance with one of said determinants and having a window for selecting one of said data at a time; means for moving the indicator plates in accordance with other of said determinants to position some of the data containing the one to be selected behind the shutter; and optical means for rendering the selected datum visible.

2. In a machine of the class described, the combination of a plurality of adjustable product plates each having thereon prefigured products in a column of lines for locating each single one of said products; a movable shutter having a window adapted to be adjusted to the individual line in said column for selecting one of said products at a time; means for moving said indicator plates whereby the column of lines containing the product to be displayed is in an effective position; and optical means for rendering the selected product visible.

3. In a machine of the class described, the combination of a totalizer having denominational order means for representing amounts; units, 75 tens, and hundreds denominational order control

means differentially positioned under control of corresponding denominational order means of the totalizer according to the various digits of a multi-digit amount represented thereby; a plate having thereon data arranged in columns and lines; electrically operated means controlled by the units order differentially positioned control means for selecting a column of data; electrically operated means controlled by the hundreds order differentially positioned control means for selecting a group of lines of data from the selected column; electrically operated means controlled by the tens order differentially positioned control means for selecting a line of data from the selected group of lines; and means for rendering the selected line of data visible.

4. In a machine of the class described, the combination of a totalizer having denominational order means for representing amounts; units, tens, and hundreds denominational order control means differentially positioned under control of corresponding denominational order means of the totalizer according to the various digits of a multi-digit amount represented thereby; a plate having data arranged thereon in columns and lines; a movable shutter having a window for selecting one line of data at a time; electrically operated means controlled by the units order differentially positioned control means for selecting a column of data; electrically operated means controlled by the hundreds order differentially positioned control means for selecting a group of lines from the selected column; and electrically controlled means controlled by the tens order differentially positioned means to operate said shutter to select only one line of data from the selected group of lines.

5. In a machine of the class described, the combination of a totalizer having denominational order means for representing amounts; units, tens, and hundreds denominational order control means differentially positioned under control of corresponding denominational order means of the totalizer according to the various digits of a multi-digit amount represented thereby; a plate having data arranged thereon in columns and lines; a movable shutter having a window for selecting one line of data at a time; electrically operated means controlled by the units order differentially positioned control means for selecting a column of data; electrically operated means controlled by the hundreds order differentially positioned control means for selecting a group of lines from the selected column; and means controlled by the tens order differentially positioned control means for operating said shutter to enable said window to select a single line from the selected group of lines; and means to render the selected line visible.

6. In a machine of the class described, the combination of a totalizer having denominational order elements for representing the digits of amounts; denominational members positioned under control of said elements according to the amount in said totalizer; a plurality of members each having data thereon arranged in columns and lines, said data being product tables according to different price unit charges; manipulative means; electrically operated means controlled by said manipulative means to select an indicator plate according to the unit price desired; electrically controlled means controlled by said differentially positioned means for selecting a column, selecting a group of lines from said column and a line from the selected group; a viewing

screen; and means cooperating with the selecting means to project the selected data on said viewing screen.

7. In a machine of the class described having a totalizer, the combination of means differentially positioned according to the amount standing on the totalizer; a plurality of indicator plates arranged on a plurality of rotating discs each plate having a group of lines of data, the groups of lines on all plates constituting a table of products based on a definite price unit; and means controlled by said differentially positioned means to select one of said discs, to select a group of lines of data from the selected disc and to select a line from the selected group of lines.

8. In a machine of the class described, the combination of a totalizer having denominational elements settable to represent the digits of a multi-digit amount; units, tens, and hundreds denominational means differentially positioned according to the values standing on corresponding denominational elements of the totalizer; a plurality of indicator plates arranged on a plurality of rotating discs each plate having a group of lines of data, the groups of lines on all plates constituting a table of products based on amounts on said totalizer times a definite fixed amount; common means for supporting all of said discs; means controlled by the hundreds order differentially positioned means for operating said common means to select one of said discs carrying a plurality of the indicator plates; means controlled by the units order differentially positioned means for rotating the selected disc to select one of the indicator plates thereon containing a group of lines of data; and means controlled by the tens order differentially positioned means for selecting one of the lines from the group of lines of the selected disc.

9. In a machine of the class described, the combination of a totalizer having denominational elements settable to represent the digits of a multi-digit amount; units, tens, and hundreds denominational means differentially positioned according to the values standing on corresponding denominational elements of the totalizer; a plurality of indicator plates each having arranged thereon a group of lines of data, the groups of lines on all plates constituting a table of products based on consumption amounts times a definite unit price; a plurality of discs each carrying a definite group of said indicator plates; common means for supporting all of said discs; means controlled by the hundreds order differentially positioned means for operating the common means to select one of said discs as determined by the amount of consumption in the hundreds order; means controlled by the units order differentially positioned means for rotating the selected disc to select one of the indicator plates thereon as determined by the amount of consumption in the units order; and means controlled by the tens order differentially positioned means for selecting one of the lines from the group of lines of the selected disc as determined by the amount of consumption in the tens order.

10. In a machine of the class described, the combination of a totalizer; differential means; total taking control means to control the operation of the totalizer and the differential means to cause the totalizer to be cleared and the differential means to be differentially positioned according to the amount cleared from the totalizer; a plurality of indicator plates each having

arranged thereon a group of lines of data, the groups of lines on all plates constituting a table of products; a plurality of members each carrying a definite group of said indicator plates; a common support for all of said members; a shutter having a window for selecting one line of data at a time; means controlled by the hundreds order differentially positioned means upon the clearing of the totalizer for operating said common member to select one of said discs as determined by the value of said hundreds order; means controlled by the units order differentially positioned means for rotating the selected disc to select one of the groups of lines as determined by the value of said units order; and means controlled by the tens order differentially positioned means for operating said shutter to move the window to select a particular line of the selected group of lines as determined by the value of the tens order.

11. In a machine of the class described the combination of a totalizer; differential means; total taking control means to control the operation of the totalizer and the differential means to cause the totalizer to be cleared and the differential means to be differentially positioned according to the amount cleared from the totalizer; a plurality of indicator plates each having arranged thereon a group of lines of data, the groups of lines on all plates constituting a table of products; a plurality of members each carrying a definite group of said indicator plates; a common support for all of said members; an adjustable shutter having a window for displaying one line of data at a time; a viewing screen; optical means and illuminating means arranged to project a product onto the viewing screen to render the selected product visible; means actuated by the hundreds order differentially positioned means upon the clearing of the totalizer for operating said common member to move one of said discs, as determined by the value of said hundreds order, into cooperative relation with the projecting means; means controlled by the units order differentially positioned means for rotating the selected disc to move one of said indicator plates of the selected disc, as determined by the value of the units order, into the path of the projecting means; and means controlled by the tens order differentially positioned means for operating said shutter to enable said window to select a particular line of the selected group of lines as determined by the value of the tens order to be projected on the viewing screen.

12. In a machine of the class described, the combination of a plurality of indicator plates each having thereon data in columns and lines; a viewing screen for displaying one of said data at a time; optical means for selecting a column and a line in that column and rendering visible in the window said selected data of a selected indicator plate; means for selecting an indicator plate; and means for moving a selected indicator plate into effective position in relation to said optical means.

13. In a machine of the class described, the combination of a plurality of product plates, each having products prefigured from consumption values and a unit price and distributed thereon in a column subdivided into lines for locating each single one of said products; a common support for the plates; an adjustable shutter having a window through which only one of the products may be displayed; means for moving the support to select certain ones of the prod-

uct plates for cooperation with the shutter; means for moving said selected product plates on the support to bring one of the selected plates opposite the shutter; and means for adjusting the shutter to bring the window to any of said lines for displaying one of said products from said one of the selected plates.

14. In a machine of the class described, the combination of a viewing screen; projecting means; a plurality of product plates consisting of diapositives, each having thereon products prefigured from consecutive consumption amounts and a unit price and distributed in columns and lines for locating each single one of said products; a common support for said plates; means for moving said support to selectively move any one of said plates into the range of the projecting means so that an image of the products thereon may be projected therefrom; and a plurality of means jointly operable to select one of said products for projection on said screen, one of said means comprising a mirror differentially adjustable to reflect any one of the columns from the image projected from the selected diapositive, another of said plurality of means comprising a mirror differentially adjustable to reflect a selected portion of said selected column, and the third of said plurality of means comprising an apertured shutter adjacent the viewing screen for blocking from the viewing screen all of the reflected portion of the selected column except one line thereof, said shutter being differentially adjustable to select the desired one of the lines of the reflected portion of the selected column, whereby upon the selective delimitations of the image projected from the diapositive only the desired product will be visible on the screen.

15. In a machine of the class described, the combination of a plurality of product tables consisting of diapositive members, each having products thereon consecutively distributed in columns subdivided into lines, and prefigured from consumption amounts and a unit price, each diapositive member being selectable according to a unit price and the products thereon being selectable according to a consumption amount; a viewing plate; a projecting means for projecting said products contained on a selected diapositive member; means for supporting the diapositive members; means for moving the supporting means to selectively place one of the diapositive members into the path of the projecting means; a balance totalizer for computing a multi-digit consumption amount and having denominational elements settable to the digit values of said consumption amount; means controlled by one of the denominational elements of the balance totalizer according to its digital setting for selecting a column of said projected products; means controlled by another denominational element of said totalizer according to its digital setting for selecting a portion of said selected column of projected products for projection toward said plate; and means controlled by a third denominational element of said totalizer according to its digital setting for selecting one of the lines of the selected portion of the selected column, so that only said one line is projected on said plate.

16. In a machine of the class described, the combination of a plurality of product tables consisting of diapositive members, each having products thereon consecutively distributed in columns subdivided into lines, and prefigured from consumption amounts and a unit price, each diapositive member being selectable according to a unit

price and the products thereon being selectable according to a consumption amount; a viewing plate; a projecting means for projecting the products contained on any one of the diapositive members; means for supporting the diapositive members; means for moving the supporting means to selectively place one of the diapositive members into the path of the projecting means; a balance totalizer for computing a multi-digit consumption amount and having denominational elements settable to the digit values of said consumption amount; differential mechanisms corresponding to each of said denominational elements and differentially settable to represent digits; control means for controlling the cooperation of said balance totalizer and said differential mechanisms in a total-taking operation to enable the denominational elements of the balance totalizer to be cleared of the digit values thereon and control the differential setting of the differential mechanisms according to these digit values; means controlled by one of said differential mechanisms, according to its digital setting, for selecting a column of said projected products; means controlled by another of said differential mechanisms, according to its digital setting, for selecting a portion of said selected column for projection toward said plate; shiftable means for blocking all but one line of the selected portion of the selected column from reaching the plate; and means controlled by a further one of said differential mechanisms, according to its digital setting, for shifting the blocking means to select which one of the products will reach the plate.

17. In a machine of the class described, the combination of a plurality of diapositive members each having therein in consecutive order in columns of lines, products prefigured from consumption values and a unit price whereby the three lowest denominational order digits of the consumption value determine the column, the portion of the column, and the line containing the product corresponding to the consumption amount and the price determines which of the diapositive members is to be used; a movable support common to the diapositive members; key banks for controlling the selection of the members; an actuator for the support for the diapositive members; means controlled by any depressed key for stopping the support actuator when the support has reached a set position determined by the depressed key; an add and subtract totalizer for computing a consumption value; denominational members differentially settable according to the three lowest denominational order digits of a consumption value; means for controlling the operation of the totalizer and differential members to perform a total-taking operation to clear the totalizer and set the differentially settable members according to said three lowest order digits of the consumption value; a shutter provided with an aperture and adapted to be adjusted to any one of a group of products under control of one of said differentially settable members; an optical system including two correlated mirrors, one of said mirrors being adjusted under control of a second of said differentially settable members to select one of the columns of products from the diapositive member and the other of said mirrors being adjusted under control of a third of said differentially settable members for selecting a group of products from said selected column and for directing the group of products to the shutter so that one

product of the group may be selected thereby; and means set in said total-making operation to render the optical system operative to make the selected product visible.

- 5 18. In a machine of the class described, the combination of a plurality of diapositive members each having thereon in consecutive order in columns of lines, products prefigured from consumption values and a unit price whereby the three lowest denominational digits of the consumption value determine the column, the portion of the column, and the line containing the product corresponding to the consumption value and the price determines which of the diapositive members is to be used; a movable support common to the diapositive members; special key banks for controlling the selection of the members; an actuator for the support for the members; means, normally inoperative, controlled by any special key depressed for stopping the support actuator when the support has reached a set position determined by said key; an add and subtract totalizer for computing a consumption value; denominational members differentially settable according to the three lowest denominational digits of a consumption value; means for controlling the operation of the totalizer and differential members to perform a total-taking operation to clear the totalizer and set the differentially settable members according to the three lowest order digits of the consumption value; a shutter provided with an aperture; means to adjust said shutter to enable the aperture to select any one of a group of products under control of one of said differentially settable members; means controlled by said support stopping means for preventing the operation of the shutter adjusting means until the stopping means has operated to arrest the support; an optical system including two correlated mirrors; means to adjust one of said mirrors under control of a second of said differentially settable members to select one of the columns of products from the diapositive member; means to adjust the other mirror under control of a third of said differentially settable members for selecting a group of products from said selected column and for directing the group of products toward the shutter so that one of the group may be selected thereby; means set in said total-taking operation to render the stopping means operative and there-through to render the shutter adjusting means operative to enable the complete selection of a product to be made; and means cooperative with the optical system and the shutter for rendering the selected product visible.
- 10 19. In a machine of the class described, the combination of a totalizer upon which amounts may be set; differentially settable members; control means for controlling the cooperation of the totalizer and the differentially settable members to clear an amount from the totalizer and set the members differentially according to said amount; an element having thereon data related to amounts settable in said totalizer, said data being arranged in columns and lines; viewing means; and a plurality of electrically operated means controlled by said differential members according to the setting thereof, one of said electrically operated means selecting a column of data on said element, another selecting a portion of said selected column, and a third selecting a line from the selected column and selected portion of said column, said electrically operated means jointly cooperating to select from the data
- 15 20 25 30 35 40 45 50 55 60 65 70 75

on the element that datum related to the amount cleared from the totalizer and to present the selected datum at the viewing means.

20. In a machine of the class described, the combination of a totalizer upon which amounts may be set; an element having thereon data related to amounts settable in said totalizer, said data being arranged in columns and lines; electrically operated means differentially operable for selecting a column of data on said element; electrically operated means differentially operable for selecting the data in the lines of a portion of said selected column; electrically operable means differentially operable for selecting the datum in one of the lines of the selected portion of the selected column; electrical circuits having means therein to control the differential operation of the several electrically operated means; means settable according to the amount in the totalizer for selectively rendering said electrical circuits effective to control the electrically operable means, said totalizer, therefore, causing the selection, from all the data on the element, of only that datum which is related to the amount on said totalizer; and means cooperating with the selecting means for rendering the selected datum visible.

21. In a machine of the class described, the combination of a totalizer having denominational order elements settable according to the digits of a multi-digit amount; a preset-amount plate having amounts thereon related to various multi-digit amounts which may be set in the totalizer, said preset amounts being arranged in columns and lines thereon; denominational control means settable according to the setting of the various denominational order elements of the totalizer; electrically operated means controlled by the denominational control means for the units denominational order for selecting a column of the preset amounts; electrically operated means controlled by the denominational control means for the hundreds denominational order for selecting a group of lines of preset amounts; electrically operated means controlled by the denominational control means for the tens denominational order for selecting a line containing one of the preset amounts, the several electrically operated means cooperating to select a single preset amount under the joint control of the various denominational control means individually settable according to the units, tens, and hundreds digits of a multi-digit amount contained in said totalizer, by selecting a single preset amount from a group of preset amounts selected from a column of preset amounts selected from the preset-amount plate; and means cooperating with said selecting means to render the selected product visible.

22. In a machine of the class described, the combination of a diapositive member having thereon amounts arranged in definite areas of the member; a viewing screen; a light-projecting means for projecting light through the diapositive member to project the amounts thereon; a light-reflecting means variously settable to reflect a group of amounts projected from a selected area of the member; a second light-reflecting means to receive the reflected amounts and variously settable to reflect the amounts in a portion of the selected area of the member which was reflected by the first reflecting means; and a shutter upon which the amounts in the selected portion of the selected area are reflected, said shutter having therein a window which allows

only the light from an area corresponding to a single amount to pass through the shutter to the viewing screen and thus further delimits the selected area to that occupied by one of said amounts, and said shutter being variously settable to enable the window to select one of the amounts in the selected portion of the selected area for projection onto the viewing screen.

23. In a machine of the class described, the combination of a product table consisting of a diapositive member having thereon products consecutively distributed in columns subdivided into lines, and precomputed from consumption amounts and a unit price, the products being selectable according to consumption amounts; a viewing screen; a projecting means for projecting the products on the diapositive member towards the viewing screen; and means for selectively controlling the light path from the projecting means to the viewing screen to select one of the products from the diapositive member, said light path control means including a first reflector differentially settable to select one column of products on the diapositive member and reflect it onto a second reflector which is differentially settable to select a portion of the column and reflect it onto a shutter having a window therein which allows the light passing through only one line of the selected portion of the selected column to reach the viewing screen to render the selected product visible thereon, which shutter is differentially settable to select which line will be visible.

24. In a machine of the class described, the combination of a plurality of product tables consisting of diapositive members, each having products thereon consecutively distributed in columns subdivided into lines, and prefigured from consumption amounts and a unit price, each diapositive member being selectable according to a unit price and the products thereon being selectable according to a consumption amount; a viewing plate; a projecting means; means for supporting the diapositive members; means for moving the supporting means to selectively place one of the diapositive members in front of the projecting means so that an image of the product table can be projected therefrom; a mirror differentially settable to reflect a portion of the image occupied by one column of products; a second mirror differentially settable to reflect a portion of the selected column of products toward said viewing screen; and a shutter having a window therein and operable to intercept all but one of the products reflected toward the viewing screen, said shutter being differentially settable to select a desired one of the products which will be visible on the viewing screen.

25. In a machine of the class described, the combination of a totalizer having a plurality of denominational elements settable according to the digits of a multi-digit amount; diapositive means having thereon a plurality of related amounts, each amount being selectable according to the various digits making up the multi-digit amount in the totalizer; means controlled by one of the denominational elements of the totalizer according to its digital setting for selecting a group of said related amounts; means controlled by another of the denominational elements of the totalizer according to its digital setting for selecting the amounts forming a portion of the selected group of related amounts; means controlled by a further one of said denominational elements of the totalizer according to its

digital setting to select one of the amounts included in the selected portion of the selected group of related amounts; said totalizer elements therefore jointly controlling the selection of one of the related amounts by the selective elimination of other of the related amounts; and means to render the selected one of the related amounts visible.

26. In a machine of the class described, the combination of a product table consisting of a diapositive member having thereon products consecutively distributed in columns subdivided into lines, and precomputed from consumption amounts and a unit price, the products being selectable according to consumption amounts; a viewing screen; a projecting means for projecting the products on the diapositive member towards the viewing screen; means for selectively controlling the light path from the projecting means to the viewing screen to select one of the products from the diapositive member, said light path control means including a first reflector differentially settable to select one column of products on the diapositive member and reflect it onto a second reflector which is differentially settable to select a portion of the column and reflect it onto a shutter having a window therein which allows the light passing through only one line of the selected portion of the selected column to reach the viewing screen to render the selected product visible thereon and which is differentially settable to select which line will be visible; a balance totalizer for computing consumption amounts upon which said products are based; and means controlled by said balance totalizer for controlling the differential setting of the first reflector, the second reflector, and the shutter according to the consumption amount to

thereby select from the table the product corresponding to the consumption amount computed by the balance totalizer.

27. In a machine of the class described, the combination of a balance totalizer for computing consumption amounts and having units, tens, and hundreds denominational order elements settable according to the digits of these amounts; diapositive means having thereon five hundred precomputed products of a unit price times five hundred consumption amounts which may be computed in said balance totalizer; means controlled from the hundreds denominational order element of the totalizer for selecting those products based on consumption amounts having a hundreds order digit corresponding to the setting of the hundreds denominational order element of the balance totalizer; means controlled from the units denominational order element of the balance totalizer for selecting those products based on consumption amounts having a units order digit corresponding to that set on the units denominational order element of the balance totalizer; an apertured shutter controlled from the tens denominational order element of the balance totalizer for selecting those products based on consumption amounts having a tens order digit corresponding to that set on the tens denominational order element of the balance totalizer; said three selecting means by their joint cooperation selecting, from the five hundred products, that particular product which is based on the hundreds, tens, and units digits of the consumption amount set on the balance totalizer; and means for rendering the selected product visible.

HELMUT GELLER.
HANS DRIESCHER.
